UNITED STATES PATENT OFFICE.

MILON J. TRUMBLE, OF LOS ANGELES, CALIFORNIA, ASSIGNOR, BY MESNE ASSIGNMENTS, TO SHELL COMPANY OF CALIFORNIA, OF SAN FRANCISCO, CALIFORNIA, A CORPORATION OF CALIFORNIA.

PROCESS AND APPARATUS FOR CONVERTING PETROLEUM-OILS.

1,281,884.

Specification of Letters Patent.

Patented Oct. 15, 1918.

Original application filed July 19, 1915, Serial No. 40,794. Divided and this application filed July 19, 1915. Serial No. 40,795.

To all whom it may concern:

Be it known that I, MILON J. TRUMBLE, a citizen of the United States, residing at Los Angeles, in the county of Los Angeles, State 5 of California, have invented a new and useful Process and Apparatus for Converting Petroleum-Oils, of which the following is a specification.

This application is a division of an accompanying application for an apparatus for converting petroleum oils, serial No. 40,794, filed July 19, 1915.

The invention relates to the art of refining petroleum oils, and its principal object is to provide a process and apparatus by which petroleum oils of high specific gravity may be converted into oils of much lower specific gravity. There is at the present time a large production of oils of high 20 specific gravity, hereinafter called heavy oils, and such oils are of much less commercial value than oils of low specific gravity hereinafter called light oils. The process and apparatus described herein has been used on 25 a large scale to convert heavy oils into light oils.

The conversion of heavy oils into light oils has been previously accomplished in a crude way by various methods which are 30 known in the art as "cracking" processes. Previous inventors have devised many forms of apparatus for cracking oils. This they have sought to accomplish by heat, with or 35 without pressure, in some cases using various catalytic agents such as nickel, alumina, etc. The process described herein has the following advantages.

First, the process described herein is a 40 continuous one, in which a definite volume of heavy oil is maintained in rapid motion at a cracking temperature through apparatus 45 forming a closed ring, light oil vapors being removed as fast as formed, and fresh oil being continually supplied to take the place of the vapors withdrawn so that the volume of oil in the closed ring is maintained practically constant. In actual operation in 50 large refineries the apparatus described has demonstrated that it can operate over a long period, continuously converting large quantities of heavy oils into light oils.

Second, it provides an apparatus in which the actual volume of heated oil is small, the

large capacity of the apparatus being due to the high efficiency of the various parts. 55 Where the ordinary form of cracking stills is used a large capacity can be economically obtained only by using large units, which, when running contain a large quantity of oil heated to such a temperature that it will 60 spontaneously ignite when released into the air. A leak or break in such a still will result in the ejection of large volumes of highly heated oil which burns with great violence. This condition becomes more 65 serious where the still is used under pressure. With the small volume of oil contained in the apparatus disclosed herein such serious 70 conflagrations cannot occur. The apparatus therefore combines large capacity with great safety.

Third, the oil contained in the closed ring described above is forced through the heating means at a high velocity. The heating means comprises a series of pipes suitably 75 connected to form a single continuous heating coil. The oil enters the coil at a moderate velocity and as it passes through the coil large quantities of vapor are gradually produced therein. This vapor remains intimately mixed with the body of the oil due to its rapid motion forming a foam which gradually increases in volume and consequently travels with an increasing velocity through the heating coil. 85

The high velocity of the oil in the closed ring produces several important results among which the following may be mentioned:

(a) This high velocity results in a high 90 efficiency of heat transference, enabling large quantities of heat to be transferred to the oil from a relatively small heating surface.

(b) This high velocity results in a very 95 uniform heating of the foamy mixture of oil and vapors so that there is no danger of producing undesirable products by local overheating.

(c) This high velocity prevents the deposition of carbon, or other solid or viscous materials on the interior of the heating coil so that the apparatus cannot become clogged or the efficiency of the heating surface destroyed by such deposition. 100

(d) This high velocity prevents unequal

heating of the heating coil as all parts of the coil are uniformly cooled by the oil flowing therethrough. The uniform and moderate heating of the coil gives the apparatus a 5 long life and results in great safety of operation.

Fourth, the apparatus disclosed herein is especially adapted to work under pressure. It is a well known fact that the character of 10 the products obtained from petroleum oils by cracking is not only dependent on the temperature but also to a very great degree on the pressure under which the cracking takes place. The heating coil being composed of 15 pipes is well adapted to stand high pressures even when heated, and these pressures are readily controlled by an adjustable valve through which the heating coil discharges.

Fifth, the apparatus is especially adapted 20 to maintain constant the conditions under which the oil circulates through the closed ring, and to maintain constant the composition of the oil and the percentage of solid matter carried therein. Solid substances 25 may be contained in the oil introduced into the apparatus, and solid hydrocarbons or even free carbon may be formed in the apparatus. Such solid substances cannot be vaporized and it is important that the 30 circulating oil be relieved of them at the same rate at which they are formed if the composition of the oil is to be maintained constant. This condition of equilibrium is maintained in the closed ring by a constant 35 withdrawal of light vapors, a constant withdrawal of heavy oil and included solids, and a constant replacement of the volume so withdrawn by fresh oil. The heavy oil can be conveniently withdrawn from the bottom 40 of the settling tank forming a portion of the closed ring.

In practice a very small flow of heavy oil through the relief pipe is sufficient to prevent undue accumulations of objectionable 45 solids in the body of the circulating oil. For example with California oils on which the apparatus has been commercially operated the amount of oil withdrawn through the relief pipe is less than five per cent. of 50 the oil introduced through the makeup pump.

The apparatus described herein differs greatly in method of operation and results from the ordinary forms of cracking stills. 55 In such stills a constant character of product cannot be obtained as the condition of the oil in the still and consequently the character of the product obtained changes gradually as the process proceeds.

60 In the apparatus described herein the oil circulating in the closed ring is maintained under constant conditions of temperature, pressure, and composition, so that the character of the product obtained is constant. 65 However, the temperature, pressure and com-

position of the oil in the closed ring may each or all be varied so that the character of the product obtained can be varied within certain practical limits.

Sixth, the apparatus described herein is 70 provided with means for fractionating the vapors taken off and for returning certain undesirable constituents thereof to the ring for retreatment. This is important as it may be undesirable, or even impossible, in 75 the practical operation of the apparatus to regulate the conditions in the closed ring to such a degree that only the desired product is produced. It is especially easy to operate various forms of fractionating apparatus 80 with the apparatus disclosed herein as the character of the vapors given off, and the rate of flow thereof, is constant. The fractionating apparatus can therefore be operated under certain constant conditions 85 with a consequent large capacity and high efficiency.

In the drawings which are for illustrative purposes only:

Figure 1 is a plan view showing a certain 90 arrangement of apparatus which is adapted to carry on the process.

Fig. 2 is an elevation of said apparatus.

Fig. 8 shows a schematic diagram illustrating the process in a simple form. 110

Fig. 9 shows a similar diagram illustrating a modification of the process.

In the following description the term crude oil is used to designate the oil to be treated. This may be a natural oil in its 115 raw state or it may be the product of previous refining or other treatment.

The apparatus illustrated by the drawings consists of a heating coil 1, a vapor releaser 2, a settling tank 3, dephlegmators 4, 120 and a condenser 5. A circulating pump 6 delivers oil from the settling tank 3 to the coil 1, crude oil is delivered to the coil 1 from a tank 7 by a make-up pump 8, and heavy oil with its included solids is drawn 125 from the settling tank 3 by a relief pump 9.

The heating coil 1 is placed in a furnace 10 and consists of a series of pipes 11 joined into a continuous coil by pipe fittings 12 and 13. An inlet T 14 and an outlet elbow 15 130

are secured on either end of the coil 1. Oil burners 16 of any well known form extend into the furnace 10, being fed with fuel from a fuel supply pipe 17.

5 The vapor releaser 2 may be of any suitable form. The form shown consists of a shell 18 having secured thereto a top 19 and a conical bottom 20. A hot mixture pipe 21 discharges through the top 19 being connected to a pressure control valve 22 which is connected to the elbow 15. Deflecting cones 23 are secured on pipe members 24 which are connected by T's 25 to vapor outlet pipes 26. The vapor outlet pipes 26 pass through the shell 18, a tight joint therewith being insured by flanges 27. The cones 23 are of such a diameter that a small annular space is left between their outer edge and the inner wall of the shell 18. The pipe members 24 have perforations 28 cut therein. The vapor releaser may be heat insulated by proper covering material, or preferably it may be supported in a stack 29, as shown, being partially heat insulated by the use of a fire brick wall which surrounds it. An opening 30 connects the lower part of the stack with the interior of the furnace 10. An annular space 31 allows hot gases to ascend between the vapor releaser 2 and the wall of the stack.

The settling tank 3 illustrated consists of a shell 32 having a tight top 33 and a conical bottom 34. A residuum outlet pipe 35 connects the bottom 20 of the releaser 2 with the top 33 of the settling tank 3. A series of perforated deflecting and mixing cones 36 may be located in the settling tank 3 if desired. Pet cocks 37 allow the height of liquid in the settling tank to be readily determined. The settling tank may have heat insulation 38 applied thereto. If desired the settling tank 3 may be dispensed with, the bottom of the vapor releaser 2 being utilized as a settling tank. For clearness in description the settling tank is shown as a separate piece of apparatus.

An outlet opening 39 is provided in the side of the tank 3, a pipe 40 connecting this outlet with the circulating pump 6. A pipe 41 connects the pump 6 with the inlet T 14 to which is also connected the crude oil inlet pipe 42 which is fed from the tank 7 through a pipe 43 and the make-up pump 8. A relief pipe 44 connects the relief pump 9 to the conical bottom 34 of the settling tank 3.

A vapor column 45 connects the vapor outlet pipes 26 to the lower portion of one of the dephlegmators 4. These may be of any of the well known forms, those illustrated consisting of a shell 46 having a tight cover 47 and a conical bottom 48. A series of condensation plates 49 extend across the interior of the shell 46 having openings 50 formed therein, the openings 50 having a

raised lip 51 so that condensates can collect on top of each plate 49, the openings 50 in the different plates being staggered with relation to each other. The top portion of the first dephlegmator is connected to the bottom of the second dephlegmator by a pipe 52.

Any form of condenser 5 may be used. That illustrated consists of a shell 53 having tight ends 54 and inner heads 55 which divide the interior of the shell into a water inlet space 56, an oil space 57 and a water outlet space 58. Tubes 59 are tightly secured in the heads 55 connecting the spaces 56 and 58 and extending through the space 57. A vapor inlet fitting 60 opens into the top of the space 57 and a distillate outlet fitting 61 delivers light distillate to a pipe 62 from the bottom of that space. Water is supplied to the spaces 56 and 58 and to the interior of the tubes 59 by a water inlet pipe 63, this water being discharged through a water outlet pipe 64. The top portion of the last dephlegmator 4 is connected to the vapor inlet fitting 60 through a pipe 65. A distillate discharge pipe 66 connects to the lower end of the conical bottom 48 of the first dephlegmator 4, and a similar pipe 67 is similarly connected to the second dephlegmator 4. The pipe 67 may be connected with a distillate return pipe 68 through a valve 69, and pipe 67 may also be connected to the pipe 68 through a valve 70. The pipe 66 may also be connected to a heavy distillate discharge pipe 71 through a valve 72, and the pipe 67 may be connected to a heavy distillate discharge pipe 73 through a valve 74. The fuel supply pipe 17 connects into a T 75 to which are connected valves 76 and 77. A fuel pipe 78 connects into the valve 76 and a pipe 79 connects the valve 77 with a T 80 into which is connected a valve 81, this valve being connected to a heavy oil discharge pipe 82. The T 80 is connected to the pump 9 through a pipe 83.

The method of operation of the apparatus is as follows:

Crude oil is pumped to the inlet T 14 through the pipe 42 by the make-up pump 8, this oil being drawn through the pipe 43 from the tank 7. Oil from the inlet T 14 flows through the pipes 11 and the fittings 12 and 13 to the outlet elbow 15 and through the valve 22 to the pipe 21. It is discharged from the pipe 21 into the vapor releaser 2 flowing downwardly therethrough and through the pipe 35 into the settling tank 3. As soon as sufficient oil collects in the settling tank 3, which can be ascertained by the pet cocks 37, the circulating pump 6 is started and the oil is forced around the closed ring of apparatus consisting of the pipe 41, the pipes 11, fittings 12 and 13, the pipe 21, the vapor releaser 2, the pipe 35, the settling tank 3, the pipe 40, and the pump 12 13.

6. The burners 16 are then lighted, oil being supplied from the pipe 17. It is necessary to fill the various parts of the closed ring with oil and to put this oil into rapid motion before the burners are lighted as there would otherwise be danger of too rapidly vaporizing the oil in the pipes 12. The pipe 17 may be supplied with fuel through the pipe 78, the valve 76 being open and the valve 77 being closed, or the valves 76 and 81 may be closed and the valve 77 opened, in which case oil is fed into the pipe 17 through the valve 77 from the pipe 83, this oil being taken off from the settling tank 3 through the pipe 44 and the pump 9. When the oil taken off from the settling tank through the pipe 44 is not used for fuel purposes, the valve 77 may be closed and the valve 81 opened, in which case the oil is delivered to suitable tankage not shown through the pipe 82. The flame and hot gases of the burners 16 play against the pipes 11 of the heating coil 1 and escape through the opening 30 into the stack 29 where they ascend through the annular space 31 between the shell 18 and the inner wall of the stack. The oil in the closed ring is rapidly heated, and as it enters the vapor releaser 2 is spread in a thin film over the inner walls of the shell 18 by the cones 23, vapors escaping from the film passing through the openings 28 into the pipes 24 and through the vapor outlet pipes into the vapor column 45. The further course of the vapors will be set forth hereinafter.

As the oil circulates through the closed ring of apparatus above defined, vapors are continually removed by the vapor releaser and sufficient crude oil is constantly injected by the make-up pump 8 to maintain a constant volume of oil in the apparatus. The entering crude oil may contain carbon, solid hydrocarbons, sand, silt or other foreign matter. It may also contain liquids that will not be vaporized or cracked at the operating temperature of the apparatus. All of these substances as well as any similar substances formed in the oil in its circulation through the closed ring must therefore remain in the oil after it has passed through the vapor releaser 2, and unless some means were provided to dispose of them, must eventually choke the closed ring or at least render the oil in it of such a character that little evaporation or cracking could take place therefrom.

To relieve this condition, a small quantity of oil is constantly withdrawn from the extreme bottom of the settling tank 3, this material being conveniently disposed of by feeding it by means of the pump 9 and the pipe 17 to the burners 16 where it is readily burned. The oil being somewhat reduced in velocity in passing through the settling tank, any material that will settle anywhere

in the closed ring will settle to the bottom of the tank. It is not, however, necessary to provide such a settling tank, as the heavy oil may be removed from the bottom of the vapor releaser or indeed anywhere between the vapor releaser and the inlet to the heating coil.

The oil enters the heating coil 1 at a moderate velocity and is practically free from vapor. As it circulates through the heating coil a portion thereof is broken up to form a lighter hydrocarbon, the small globules of light vapor being swept on by the moving mass of oil which assumes a foamy nature. This foam greatly increases the volume of the flowing stream which therefore accelerates rapidly. The movement of the oil and vapor through the heating coils is sufficiently rapid to provide high efficiency of heat transfer between the interior of the pipes 11 and the oil, to uniformly heat the oil and vapors, so that none of it is subjected to excessive temperatures, to prevent any deposits of solid or viscous material on the interior of the pipes 11, and to prevent local overheating anywhere in the coil 1, so that the coil has a long life and is very safe to operate. The foam remains in the heating coil 1 only a very short time, being immediately passed into the vapor releaser 2 where the vapors are withdrawn from the oil. This is important as there is some danger of the vapors being further cracked if retained in the heating coil.

When operating with some sorts of crude oil, it is necessary to put some pressure on the oil in the heating coil 1 to produce a desired product. This can be readily done by partially closing the valve 22.

In practical operation, the heat of the fire, the rate of injection of crude oil, the speed of the circulating pump, the rate of withdrawal through the relief pipe 44, and the pressure are all regulated so that the oil passing through the closed ring is subjected to a definite and constantly recurring cycle of conditions. It is of course obvious that there are limits within which the various factors can be practically controlled and there are therefore practical limitations to the product that can be obtained by this process from a given oil. The product can, however, be very materially modified by a suitable modification of the conditions in the closed ring, and one great advantage of the present process is the ease with which conditions in the ring can be modified to produce the best commercial results.

The vapors in the vapor column 45 may be the desired product, in which case the dephlegmators 4 can be dispensed with, the vapors being passed directly into the condenser 5, condensed therein and passed off through the pipe 62. It may be desired to

separate the product into distillates of several gravities, in which case the dephlegmators are very convenient.

The vapor passes from the vapor column 5 to the bottom of the first dephlegmator and through a tortuous course through the openings 50 to the top. The vapors then pass through the pipe 52 to the second dephlegmator and through the openings 50 to the top thereof. The vapors in passing through the dephlegmators are gradually cooled, a heavy distillate collecting on the plates 49 and running over the lips 51 into the bottom of the first dephlegmator. A medium distillate condenses and collects in the second dephlegmator. The vapors not condensed in the dephlegmators are condensed in the condenser 5 to form a light distillate which is delivered through the pipe 62. The heavy distillate may be a desirable commercial product in which case the valve 69 is closed and the valve 72 is opened, the heavy distillate being delivered through the pipe 71 after cooling to suitable tankage. If the heavy distillate is not a desirable commercial product, the valve 72 may be closed and the valve 69 opened, the heavy distillate being delivered to the pipe 68. If the medium distillate delivered by the pipe 67 is a desirable commercial product the valve 70 is closed and the valve 74 is opened, the medium distillate being delivered after cooling to suitable tankage through the pipe 71. If this medium distillate is not a desirable commercial product by opening the valve 70 and closing the valve 74, medium distillate can be delivered to the pipe 68. Any distillate delivered to the pipe 68 is returned to the settling tank 3, being delivered onto the mixing plates 36 where it mixes with oil delivered from the vapor releaser 2 through the pipe 35, thereby being reintroduced into the closed ring for retreatment.

It will be seen that the invention consists 45 of the following original conceptions:

First, the forcing of petroleum oils through a heating coil, heated to a sufficient degree to crack the oil, at such a rate and at such a pressure that the oil can be changed into 50 a foam without danger of unduly heating portions thereof or burning the coil, it having been found by the inventor that heavy petroleum oils are changed to light ones by such a process.

Second, the immediate release of the foam so produced, the removal of vapors therefrom and the immediate recirculation and reheating of the oil to form more foam, the oil being kept in continuous motion over a 55 closed ring or path.

Third, the condensation of a portion of the vapors so produced, and the return to the closed ring of the heavy distillate so produced.

Fourth, the use of the settling tank 3 in

a closed ring and the continuous removal of heavy oil and foreign matter from the bottom of this tank, so that accumulations of solid matter in the ring is prevented and the composition of the oil in the closed ring 70 is maintained constant.

Fifth, the use of the make-up pump 8 for the purpose of maintaining constant the volume of the closed ring as vapors and heavy oil with included sediments are taken off 75 therefrom.

Sixth, the use as fuel in the burners 16 of the hot heavy oil from the bottom of the tank 3.

I claim as my invention:

1. The process of converting a heavy petroleum oil into a light one which consists in circulating the heavy oil through a closed ring, continuously heating a portion of the ring, continuously taking off light vapors 80 from the ring, continuously relieving the ring of a small amount of heavy oil, and continuously supplying fresh oil in sufficient quantities to maintain constant the volume of oil in the closed ring.

2. The process of converting a heavy petroleum oil into a light one which consists in circulating the heavy oil through a closed ring, continuously heating a portion of the ring, maintaining a pressure on the portion 85 of the ring so heated, continuously taking off light vapors from the ring, continuously relieving the ring of a small amount of heavy oil, and continuously supplying fresh oil in sufficient quantities to maintain constant the volume of oil in the closed ring.

3. The process of converting a heavy petroleum oil into a light petroleum oil which comprises, first, forcing the heavy oil through a heating coil, said coil being heated to a sufficient degree to crack the oil, said 95 heavy oil being forced through said coil at such a rate and at such a pressure that the oil is changed into foam without danger of unduly burning portions thereof, second, removing light vapors from the stream of oil, 100 third, recirculating the residuum left after said vapors are removed through said heating coil to form more foam, said oil thus being kept in continuous movement over a 105 closed path or ring, fourth, condensing a portion of the vapors so removed, the distillates so condensed being returned to the closed ring for retreatment, fifth, constantly removing a small portion of the heavy oil 110 and included solids from the ring, and simultaneously with the above steps supplying crude oil to said ring to replace any diminution in volume of the oil therein, so that the volume of oil in said ring is main- 115

tained constant.

4. An apparatus for converting heavy petroleum mixtures into light petroleum oils, comprising a heating means; a vapor releaser; means for conducting the heated mix- 120

- ture from the primary heating means to the vapor releaser; means for withdrawing light vapors from the vapor releaser; means for continuously withdrawing a portion of 5 the mixture; means for forcing the residuum from the vapor releaser through the primary heating means; and means for injecting sufficient fresh heavy oil into, said residuum to maintain the volume of oil in 10 the apparatus approximately constant.
5. An apparatus for treating liquids comprising a furnace; a burner for said furnace; a heating coil in said furnace; a vapor releaser; pipes connecting said heating 15 coil with said releaser; a series of dephlegmators; pipes conducting the vapors from said vapor releaser successively through said dephlegmators; a condenser; a circulating pump; pipes delivering the residuum from 20 said vapor releaser to the suction side of said pump; a make up pump; a crude oil supply pipe delivering crude oil to the suction side of said make up pump; pipes connecting the pressure 25 side of said make up pump and said circulating pump with the inlet to said heating coil; and a relief pipe through which a portion of the residuum from said vapor releaser can be withdrawn from the system.
- 30 6. An apparatus as in claim 5 also comprising a settling tank through which the

residuum from said vapor releaser passes on its way to said circulating pump, said relief pipe being connected into said settling tank. 35

7. An apparatus for treating liquids comprising a furnace; a burner for said furnace; a heating coil in said furnace; a vapor releaser; pipes connecting said heating coil with said releaser; a circulating pump; pipes 40 delivering the residuum from said vapor releaser to the suction side of said pump; a make up pump; a crude oil supply pipe delivering crude oil to the suction side of said make up pump; pipes connecting the pressure side of said make up pump and said circulating pump with the inlet to said heating coil; and a relief pipe through which a portion of the residuum from said vapor releaser can be withdrawn from the 45 system. 50

8. An apparatus as in claim 7 also comprising a settling tank through which the residuum from said vapor releaser passes on its way to said circulating pump; said relief pipe being connected into said settling tank. 55

In testimony whereof, I have hereunto set my hand at Los Angeles, California, this 10th day of July, 1915.

MILON J. TRUMBLE.
